UNITED STATES PATENT OFFICE.

CORNELIUS JACKSON, OF PHILADELPHIA, PENNSYLVANIA, ASSIGNOR TO
THOMAS DOLAN AND R. WILLIAMS, JR., OF SAME PLACE.

DESIGN FOR KNITTED FRINGE.

Specification forming part of Design No. **11,086**, dated March 25, 1879; application filed December 7, 1878.
[Term of patent 3½ years.]

To all whom it may concern:

Be it known that I, CORNELIUS JACKSON, of Philadelphia, Pennsylvania, have invented a new and original Design for Knitted Fringe, of which the following is a specification:

My design for a knitted fringe is shown in the accompanying drawing.

The design relates to that class of fringes which have pendent cords carrying tufts; and the feature of novelty consists in forming rings or open loops *a*, of yarn, between the tufts *b*, these rings or open loops being crossed by the pendent cords, which carry the tufts, and serving to impart a full appearance to the pendent portion of the fringe.

Irrespective of the colors employed, I claim—
The design for the pendent portion of a knitted fringe, said design consisting of tufts *b* and rings or open loops *a*, arranged alternately on the pendent cords, the latter crossing the rings or loops, as shown and described.

In testimony whereof I have signed my name to this specification in the presence of two subscribing witnesses.

CORNELIUS JACKSON.
